CLAIM

The ornamental design for a game console, as shown and described.

DESCRIPTION

FIG. 1 is a front elevational view of a game console, showing my new design;

FIG. 2 is a top plan view thereof;

FIG. 3 is a bottom plan view thereof;

FIG. 4 is a rear elevational view thereof;

FIG. 5 is a left elevational view thereof;

FIG. 6 is a right elevational view thereof; and,

FIG. 7 is a front top perspective view thereof.

The broken lines in the drawings depict portions of the game console that form no part of the claimed design.
